UNITED STATES PATENT OFFICE.

FREDERICK A. CLEVELAND, OF NEW YORK, N. Y.

BINDER.

No. 829,325.

Specification of Letters Patent.

Patented Aug. 21, 1906.

Application filed July 7, 1905. Serial No. 268,664.

To all whom it may concern:

Be it known that I, FREDERICK A. CLEVELAND, a citizen of the United States, and a resident of New York, in the county of New York and State of New York, have invented certain new and useful Improvements in Binders, of which the following is a specification.

This invention relates to a device which may be applied to binders of the loose-leaf type, the object being to provide a device of simple construction which may be used in connection with covers or binders of this class, which may be easily operated, and which will be positive in its action. The use of binders of this description is well understood, and it is not thought necessary to enter into an explanation of their operation further than to state the principal requirement, which is that any number of pages or leaves may be inserted, replaced, or taken out without disturbing the remaining leaves.

The object of my invention is to provide a device which shall meet this requirement and accomplish the desired result by the use of a simple locking mechanism which does not require separate keys or other devices to operate the same and which shall be self-contained and operated by turning the book on one side to lock the covers in any desired position and to release the same by simply reversing the position of the book. To accomplish this result, I provide an upper and lower clamping-section which may be attached to the covers of the binder. These clamping-sections are normally held apart by the action of springs contained in telescoping members attached to said clamping-sections in the usual manner. Attached to one of these clamping-sections, preferably the upper, I provide a post which carries an oscillatory pawl or dog which is adapted to engage projections on the interior of a co-operating post or casting which is secured to the lower clamping-section. This latter post or casting is adapted to telescope over the post carrying the pawl or dog. The construction of these parts is such that when the clamping-sections and attached covers are in the position shown in the drawings a free inward movement is permitted and the leaves are held between the clamping-sections by pressing the upper cover down. The pawl or dog carried by the inner post will engage the projections on the inner surface of the outer post or casting and so hold the parts in position.

The construction and operation of the device will be more fully explained in connection with the drawings accompanying this specification.

Figure 1 is a perspective side elevation of a pair of clamping-sections or binder-frames with the covers and the leaves of the book omitted. Fig. 2 is an enlarged side elevation in section of a post and casing carrying a locking mechanism. Fig. 3 is an enlarged side elevation and detail view of the post carrying the pawl or dog.

In Fig. 1 at 1 and 2 are shown an upper and lower clamping-section, respectively, which may be attached by any suitable means to the cover of the binder, or, if preferred, the covers themselves may form the clamping-section and have a locking device attached directly thereto.

At 3 3 are shown telescoping members containing springs which operate normally to separate the clamping members 1 and 2 when not held in position by means of the locking mechanism carried by the post 4 and the casing 7. The operation of this locking mechanism is on the principle of a pawl-and-ratchet device. The distinguishing features of this device are found in the construction and mode of operation of the oscillatory pawl, which is so designed that the outer end thereof will engage projections on the interior of the casing 7 when the covers are in one position and will drop out of engagement with the said projections, allowing the clamping members and covers to be separated when the same are reversed in position.

At 4 is shown a post which is secured to the upper clamping member 1 by any suitable means and preferably in such a manner that it may be rotated in relation to said clamping member. This may be done by socketing the post 4 in the clamping member 1 and holding the same in position by means of an ordinary flat-headed screw, as shown in the drawings. This screw may be secured in the post 4 by any suitable means, and by using an ordinary screw-driver in the slot thereof the post may be rotated as desired. At the lower end of this post 4 is provided a recess or slot, in which is carried a pawl 5, which is pivotally supported therein at 6. This slot is so shaped as to provide a stop to limit the movement of the pawl, so that in one position the outer end thereof will engage the projections on the interior of the casing 7 and in the other position will be out of en-

gagement with the said projections and allow the parts to be separated.

The pawl 5 is preferably in the form of a segment of a circular disk having two flat sides thereof adapted to engage the walls of the slot to limit the movement thereof, as above described. A portion of this pawl is formed with one or more projections adapted to engage corresponding projections on the interior of the casing 7. The pivot 6 is so located that gravity will operate to oscillate the pawl about this pivot as the covers are turned from one position to a reverse position. In one of the aforesaid positions the projections from said pawl will engage the projections on the interior of the casing 7 and prevent the parts from being separated. In the reverse position the pawl will be rotated by gravity about its pivot and the above-described projections will swing out of engagement and allow the members to be separated for the removal of leaves, replacing leaves, &c. It will be seen that when the covers are in the reversed position just referred to that the telescoping members 4 and 7 are free to move in and out, and when the covers are reversed the pawl will oscillate about its pivot into the position shown, and the projections from said pawl will engage the projections on the interior of the casing 7, which are preferably in the form of a screw-thread. The post 4 and the attached pawl may be rotated after pressing the clamping members together, and so effect a further tightening of the aforesaid clamping members and insure the leaves being held securely in place. The casing 7 may be secured to the lower clamping member 2 by threading the same therein as shown or by any other suitable means. This casing is adapted to telescope over the post 4 and has the inner surface thereof provided with serrations or projections which are preferably in the form of a screw-thread or spiral. The object of projections of this kind has already been described.

The recess or slot in which the pawl is located has the upper portion thereof so formed as to provide a stop to limit the movement of the pawl when the same drops out of engagement with the outer casing when the members are reversed, as already described. The rear portion of this slot is adapted to form a stop to limit the movement of the pawl in the opposite direction and to hold the same in such a position that the projections from the pawl will engage the projections on the interior of the casing 7, as already described. In this position the upper cover may be pressed down and will be held in the position to which it is so moved by the operation of the several parts, as shown.

It will be noted that the device herein shown and described as an illustration of an operative embodiment of my invention is composed of a very small number of parts

and that such parts are of a simple construction and may be easily and cheaply manufactured. It will be also noted that the device when assembled is very compact in form and that the operating parts are self-contained within the same.

I do not confine myself, however, to the exact details of construction shown and described, as it will be evident that various modifications and changes may be made therein to adapt the device to its several uses without departing from the scope of my invention.

What I claim is—

1. In a binder-lock, in combination, a pair of telescoping members, and an oscillatory pawl or dog carried by one of said members and having a portion thereof adapted to engage a coöperating portion of said member to lock said pawl in operative position.

2. In a binder-lock, in combination, a pair of telescoping members, and an oscillatory pawl or dog pivotally attached to one of said members and having a portion thereof adapted to engage a coöperating portion of said member to lock said pawl in operative position.

3. In a binder-lock, in combination, a pair of telescoping members, one of said members having a serrated surface, and an oscillatory pawl or dog carried by one of said members and having a portion thereof serrated and adapted to engage said serrated surface and also having a portion thereof adapted to engage a coöperating portion of said member to lock said pawl in operative position.

4. In a binder-lock, in combination, a pair of telescoping members, one of said members having a threaded surface, and an oscillatory pawl or dog carried by one of said members and having a portion thereof adapted to engage said threaded surface and also having a portion thereof adapted to engage a coöperating portion of said member to lock said pawl in operative position.

5. In a binder, the combination of a pair of telescoping members, one of said members having a slot therein, and an oscillatory pawl or dog positioned in said slot and adapted to engage a wall thereof to lock said pawl in position to prevent the separation of said telescoping members.

6. In a binder, the combination of a pair of telescoping members, one of said members having a slot therein, and an oscillatory pawl or dog adapted to engage a wall of said slot to lock said pawl in position to prevent the separation of said telescoping members and also adapted to engage a wall of said slot to limit the movement thereof when reversed.

7. In a binder, the combination of a pair of telescoping members, one of said members having a recess therein, and an oscillatory pawl or dog having a portion thereof adapted to engage a wall of said recess to lock said

pawl in position to prevent the separation of said telescoping members.

8. In a binder, the combination of a pair of clamping members, a post having a slot at the lower end thereof, an oscillatory pawl or dog pivotally attached to said post in said slot and having a portion thereof adapted to engage the inner surface of a casing and having a portion thereof adapted to engage a wall of said slot to lock the same in position, a casing secured to the other of said clamping members and adapted to telescope over said post, substantially as described.

9. In a binder, the combination of a pair of clamping members, a post attached to one of said clamping members, an oscillatory pawl or dog pivotally attached to said post having a portion thereof adapted to engage the inner surface of a casing and a portion thereof flattened to engage a wall of said post to lock the same in position, a casing secured to the other of said clamping members and adapted to telescope over said post substantially as described.

10. In a binder, the combination of a pair of clamping members, the post attached to one of said clamping members, an oscillatory pawl or dog having a serrated surface pivotally attached to said post having a portion thereof adapted to engage the inner surface of a casing and a portion thereof adapted to engage a wall of said post and to be held thereby in an operative position when the clamping members are in one position and adapted to drop into an inoperative position when the clamping members are reversed in position, substantially as described.

11. In a binder, the combination of a pair of clamping members, a post having a slot at

the lower end thereof adapted to carry a pawl 40 or dog therein and having a portion thereof adapted to form a stop to limit the movement of said pawl or dog, an oscillatory pawl or dog having a serrated surface pivotally attached to said post in said slot and adapted 45 to be held by said stop portion of said slot in such a position that said pawl will engage the inner surface of a casing when the members are in one position and to drop out of engagement when said members are reversed in position, a casing secured to the other of said clamping members and adapted to telescope over said post, substantially as described.

12. In a binder, the combination of a pair of clamping members, a post having a slot at 55 the lower end thereof adapted to carry a pawl or dog therein and having the walls thereof adapted to form stops to limit the movement of said pawl or dog, an oscillatory pawl or dog having a serrated surface pivotally attached to said post in said slot and adapted to be held by one of said stop-walls in such a position that said pawl will engage the inner surface of a casing when the members are in one position and to drop out of engagement 60 against the other of said stop-walls when said members are reversed in position, a casing secured to the other of said clamping members and adapted to telescope over said post, substantially as described.

Signed at New York, in the county of New York and State of New York, this 16th day of June, A. D. 1905.

FREDERICK A. CLEVELAND.
